UNITED STATES PATENT OFFICE.

ISRAEL DONALD BOYER, OF DAYTON, OHIO, ASSIGNOR TO THE NATIONAL CASH REGISTER COMPANY, OF SAME PLACE.

CASH-REGISTER.

SPECIFICATION forming part of Letters Patent No. 416,029, dated November 26, 1889.

Application filed July 8, 1889. Serial No. 316,751. (No model.)

To all whom it may concern:

Be it known that I, ISRAEL DONALD BOYER, a citizen of the United States, residing at Dayton, in the county of Montgomery and State of Ohio, have invented certain new and useful Improvements in Cash Registers and Indicators, of which the following is a full, clear, and exact description, reference being had to the accompanying drawings, in which—

- 10 Figure 1 represents a side elevation of a portion of a well-known form of cash-register having my improvement applied thereto and having the rear side of the case or cabinet removed and a portion of the frame-work broken away and some of the operating parts on the opposite side of the machine removed. Fig. 2 is a sectional side elevation of the lower and rear side of the machine, and showing the parts not illustrated in Fig. 1. Fig. 3 is a
- 15 rear elevation of a portion of the machine. Fig. 4 is a detail of the locking-bar and the rear ends of the keys. Fig. 5 is a detail of the arresting devices for the vibrating bar. Fig. 6 is a detail of the wiper-block and tripping-dog for actuating the wing.
- 20
- 25

The same letters of reference are used to indicate identical parts in all the figures.

The frame-work A, which supports the working parts of the machine, is inclosed in the usual case or cabinet B, having in its lower portion a drawer-compartment, in which is fitted a money-drawer or till C.

D are the operating-keys pivoted on the shaft E, their front ends projecting through slots in the front of the case B, and provided with numbered finger-buttons, while on their rear ends rest the usual tablet-rods F, carrying numbered indicating-tablets at their upper ends and provided with shoulders a, which are engaged by the supporting-wing G to hold up an elevated tablet-rod in the usual manner. The wing G has at one side an upward extension H, which carries the gong-hammer, and is provided with a wiper-block b, engaged upon the operation of a key by the tripping-dog c, carried on the upper rear end of the bell-crank I, which is pivoted, as at d, to the frame A of the machine, and at its lower forward end is connected by slot-and-pin connection at e to the one of the side arms J of the vibrating bar or frame K which ex-

tends across all the keys and is moved by the operation of any one of them to actuate the wing G and gong-hammer through the medium of the bell-crank I and tripping-dog c in the usual well-known manner. A flat spring f, bearing on the extension H at one end of the wing, and at the other end a coiled spring g, connected to an upwardly-extending arm h, secured to the wing and to a fixed point of the frame-work, serve to yieldingly hold the wing G, extension H, and gong-hammer in their normal positions. Pivoted to and depending from a lug i, extending rearwardly from the wing G, is a link L, the lower end of which is pivoted to the outer end of the lever M, which is pivoted to a support at j, Fig. 3, and carries at its inner end the locking-bolt N, which, when the drawer is closed, engages the slotted locking-plate O, secured to the upper rear side of the drawer, and holds the latter in its closed position. When a key is operated and the wing G pressed backward through the mechanism before described, the link L and outer end of the lever M are depressed, the inner end of the lever M lifted, and the bolt N freed from the locking-plate O, whereupon the drawer is propelled from its compartment by the spring P.

The registering mechanism may be of any suitable character; but in the machine illustrated in the drawings it is of one of the usual well-known forms employed in such machines, consisting of two banks of individual registering-wheels (shown in dotted lines in Fig. 1) carried on longitudinal shafts supported in a supplemental frame Q, the squared ends R R' of which shafts are shown in Fig. 1. The wheels of the lower bank are actuated by the weighted dogs k, pivoted to the keys D, and the wheels of the upper bank are actuated by and register the revolutions of those of the lower bank in the well-known manner.

Heretofore in this class of machines the vibrating bar K has been hung by its side arms J on the pivotal shaft E of the operating-keys, and its principal function was to furnish a common actuator for the supporting-wing and the gong-sounding and drawer-locking mechanisms. In my present improvement I give this bar additional functions to

perform, the first of which arises from so constructing and arranging it and combining it with the operating-keys as to constitute it a key-coupler which locks together all keys which are displaced from their normal position at substantially the same time and compels uniform movement in their further operation. For this purpose I hang the bar K by its arms J on a shaft S, located above and in rear of the pivotal point of the keys, and provide the lower rear edge of the bar K with a rearwardly-extending flange l, extending its entire length and resting on the upper sides of the keys. The upper side of each key, just in rear of the flange l of the bar K, is provided with a slotted lug, which forms a hook m, whose open mouth is in close proximity to the rear edge of the flange l. It results from this construction and the pivotal arrangement of the bar K above the keys D that when a key is operated the flange l will enter the mouth of the hook m, and the key be thereby locked to the bar K, as shown by the dotted lines at 1 in Fig. 1. If two or more keys are started at the same time, they will all become locked to the bar K in the same manner, and if any key-button is released by the operator its key will be carried on down and the registration of its value effected by the depression of the other key or keys which were started with it.

Another feature of my invention consists in combining a key-arrester with a movable bar, which extends across a series of keys and is moved by the operation of any one of them, and, further, in combining such bar and arrester with a series of keys which are so constructed that each of them becomes locked to said bar when partially operated, for it will be evident that if the keys are locked to said bar from the time they are displaced from their normal position until they are returned to such position, and a key-arrester be applied to said bar in such manner that the bar is arrested and held at any point where the key is released before full operation and cannot be reset until the key is fully operated, a single key-arrester so combined with such bar will act as a common arrester for all the keys and prevent the resetting of any one of them, when partially operated, until it has been operated to its full extent. As one form of such arrester, and as a suitable method of combining it with such bar, I have secured to one of the side arms J of the bar K a notched plate or rack T, having downwardly-presenting teeth. Pivoted to the frame A at a point above this rack is a bell-crank U, whose lower vertical arm m is provided with a shoulder o, which, owing to the weight of the horizontal arm p of the bell-crank and the pivotal arrangement of the latter, normally bears against the rack T, and when the latter is lifted by the operation of a key and the lifting of the bar K slips over and acts as a pawl for engagement with the teeth of the rack, so that if the key and bar be released

at any point in their upward travel the shoulder o will engage a tooth of the rack T and hold the bar K and the key which is locked to it at exactly the point where they were released. Projecting laterally from the side arm J in rear of the rack T is a pin q, which, as the key and bar K reach their full limit of upward motion, strikes the under side of and lifts the horizontal arm p of the bell-crank U, as shown by the dotted lines at 2, Fig. 1, and throws the vertical arm n away from the rack T, thereby disengaging the shoulder o from the teeth of the rack.

V is a weighted latch for holding the arm n and shoulder o away from the rack until the key and bar K are reset. It is pivoted at r to the frame-work A, and its upper rear end s has a lateral projection or is made of such width as to extend beneath and bear upward against the under side of the arm J, as shown in Fig. 5, being normally held in such position by the gravity of its enlarged and weighted opposite end. When a key is operated and the bar K and arm J lifted, the forward weighted end of the latch drops upon the stop-pin t, causing the latch to assume the position shown by the dotted lines in Fig. 1. As the operation of the key continues and the arm J is lifted and the pin q strikes the under side of the arm p of the bell-crank U and throws its arm n away from the rack T, the lower end of the arm n flips over the upper rear end s of the latch V and is held by it in the position shown by the dotted lines in Fig. 1 until, as the operated key and the bar K and arm J return to their normal position, the under side of the arm J strikes the upper rear end s of the latch V and moves the latter back to the position shown by the solid lines in Fig. 1, thereby releasing the arm n, which then falls by gravity against the rack T, ready for a fresh operation. It results from this construction and arrangement that whenever any key is substantially displaced from its normal position it cannot be returned to such position until it has been operated to its full extent and its total value registered. This feature of my invention, therefore, while useful in a machine provided with a series of individual registering-wheels—one for each key and each turned one number by the operation of its key, as above described—is perhaps more valuable in a machine provided with a registering-wheel common to and actuated to different degrees by a series of keys of different values, for in such machine it is absolutely essential to accurate registration that each key operated be actuated to its full extent. So far as this feature of my invention is concerned I do not wish to be limited either to the particular form of arresting devices applied to the vibrating bar or to the particular manner of locking the keys to said bar, it being sufficient for the purposes of the invention that there be a movable bar common to and moved by each of a number of keys, each of which key becomes locked to

said bar when operated, and an arrester which engages the bar and prevents it being reset until the operated key has been actuated to its full extent.

- 5 The combination of the arresting devices with the movable bar extending across the keys forms a novel and valuable feature of my invention independently of the locking of the keys to said bar, and may be advantageously employed in machines where the keys are not arranged to be locked to the bar—an instance which will be hereinafter pointed out in connection with the description of other features of my invention.
- 15 The next feature of my invention consists in combining with a movable bar common to and moved by each of a number of keys and an arrester for such bar a locking-bar actuated by said movable bar when any key is operated to lock the unoperated keys from operation. Any usual or suitable locking-bar may be used in this combination; but I have devised one of novel form and operating in a novel manner, and which of itself constitutes a novel feature of my invention aside from its combination with the movable bar and arrester. This novel locking-bar (lettered W in the drawings and shown in cross-section in Fig. 2) extends across the rear of the machine slightly in rear of and a little above the ends of the operating-keys D, and is pivoted at its ends in the sides of the frame-work A or other suitable supports, so as to oscillate freely in its bearings. It may be a flat bar of any suitable shape in cross-section—such as oval—or, as illustrated in the drawings, it may be substantially semi-cylindrical in form, having its side next the ends of the keys cut away or flattened. Rigidly secured to this bar at one end is an arm X, (in this instance by a collar Y and set-screw u,) the forward end of which arm is connected to an extension of one of the side arms J of the vibrating bar K by slot-and-pin connection at v. It results from this construction and arrangement of the parts that when a key is operated and the bar K and arm J lifted the forward end of the arm X will be lifted with the arm J and the locking-bar W be rocked to the position shown in Fig. 1, thereby moving over the ends of the unoperated keys and locking them from operation. The bar W is so shaped and arranged in such proximity to the ends of the keys that a slight oscillation of it by the partial operation of any key is sufficient to cause it to move over the ends of and lock the unoperated keys, and, inasmuch as the bar K is arrested and held at any point less than full operation by the arrester before described and cannot be reset until actuated to its full extent, it results that after any key has been substantially displaced from its normal position the bar W moves over the ends of all the unoperated keys and beneath the end of the partially-operated key, so that the latter cannot be reset nor any of the other keys

operated until the partially-operated key is further operated and its full value registered. The partially-operated key could not be reset before full operation for the further reason that it is locked to the flange of the bar K by its hook m and must move with said bar; but this locking of the keys to the bar K is independent of the operations of the bar W, and if the keys were of the ordinary construction, provided with no hooks and free to move up and down independently of the bar K, the result above described would be the same, for the partially-operated key when released would fall until its rear end rested on the upturned flat side of the bar W, but could go no farther. So far as this feature of the invention is concerned, therefore, the bar W operates both as a key-locking and key-arresting bar.

Another feature of my invention relates to novel means for preventing the operation of the keys while the money-drawer is open. It may be employed either in connection with or independently of the other features of the invention above described, although in the present case I have shown all my improvements associated together and applied to one machine. Loosely pivoted to one of the side arms J of the bar K is a pendent latch-arm Z, which is normally held in the position shown by the solid lines in Fig. 1 by a lateral projection w, Fig. 5, on the upper end of the vertical arm x of a bell-crank A', pivoted to the frame-work of the machine, as shown in Fig. 1, and whose other arm y is connected to the horizontal arm z of a second bell-crank B', loosely pivoted to any suitable support—in this instance hung on the bearing end of the locking-bar W—and whose vertical pendent arm a' extends down into the drawer-compartment and carries an adjusting-screw b'. When the drawer C is closed, its upper rear end bears against the forward end of the screw b' and holds the two bell-cranks and the arm Z in the position shown by the solid lines in Fig. 1. When a key is operated and the drawer released and partially propelled from its compartment, a coiled spring c' pulls the two bell-cranks into the position shown by the dotted lines in Fig. 1, whereupon the arm Z falls against the side of a bracket lug d', projecting inwardly from the frame-work A, and as the key and the arm J and bar K reach their limit of motion the lower end of the arm Z moves over and rests upon the base of the lug d' and thereby latches the arm J and bar K in the position shown by the dotted lines in Fig. 1. In this position of the parts the locking-bar W is in the position shown in Fig. 4, all the unoperated keys are locked by it, and the operated key cannot be reset, both because it is locked to the bar K, as shown at 1 in Fig. 1, and because if it were not locked to the bar K the bar W would prevent its resuming its normal position. When the drawer C is again pushed in, its rear end strikes the screw b, carried by the pendent

arm a' of the bell-crank B' , and throws the two bell-cranks back to the position shown by the solid lines in Fig. 1, thereby causing the lateral projection w on the upper end of the arm x of the bell-crank A' to knock the lower end of the latch-arm Z off the bracket-lug d' , whereupon all the parts are free to resume their normal positions of rest. (Shown by the solid lines of Fig. 1.) For the purpose of throwing out of operation this mechanism actuated by the opening and closing of the drawer, so that the machine can, when desired, be operated with the drawer either open or closed, I provide a lever C' , pivoted to the frame-work at e' , and whose lower end extends over and rests against the lug d' when the lever is in the position shown by the solid lines in Fig. 1; but when its handle f' is pulled forward until the spring-detent g' takes into the notch h' the lower end of the lever is thrown backward, so that when the drawer is opened the projection w on the upper end of the arm x of the bell-crank A' strikes against and is arrested by the lower end of the lever C' and holds the arm Z away from the lug d' , so that said arm moves freely up and down with the movements of the bar K , but its lower end cannot move over and be caught upon the lug d' .

Having thus fully described my invention, I claim—

1. In a cash register and indicator, the combination, with a series of operating-keys, of a bar extending across the tops of said keys and movable up and down therewith throughout their limit of play, to which bar the keys become locked as soon as displaced from their normal position, substantially as and for the purpose described.

2. In a cash register and indicator, the combination, with a series of pivoted operating-keys, of a bar extending across the tops of said keys in rear of their pivotal point and movable up and down therewith throughout their limit of play, to which bar the keys become locked as soon as displaced from their normal position, substantially as and for the purpose described.

3. In a cash register and indicator, the combination, with a series of pivoted operating-keys, each provided with a hook, of a bar extending across said keys in front of said hooks and movable up and down with the keys throughout their limit of play and arranged to be engaged by the keys which are displaced from their normal position, substantially as and for the purpose described.

4. In a cash register and indicator, the combination, with a series of pivoted operating-keys, each provided with a hook on its upper side in rear of its pivotal point, of a vibrating bar pivoted on a support above said keys and extending across the same immediately in front of their hooks, substantially as and for the purpose described.

5. In a cash register and indicator, the combination, with a series of operating-keys and

a movable bar extending across said keys and moved by the operation of any of them, of a rack-and-pawl arrester applied to said bar to prevent it being reset after being moved by the partial operation of a key, and arranged to release the same at the completion of the positive stroke of the key, substantially as and for the purpose described.

6. In a cash register and indicator, the combination, with a series of operating-keys, of a movable bar extending across said keys and moved by the operation of any of them, a rack on said bar, and a pawl arranged to engage the rack when the bar is moved by the partial operation of a key to prevent the bar being reset until it has been given its full movement by the full operation of such key, substantially as and for the purpose described.

7. In a cash register and indicator, the combination, with a series of operating-keys, of a movable bar extending across said keys and moved by the operation of any one of them, a rack on said bar, a pawl arranged to engage the rack when the bar has been displaced from normal position by the partial operation of a key, a trip for disengaging the pawl from the rack when the bar has reached its limit of movement, and a latch for holding the pawl and rack out of engagement while the bar is being reset, substantially as and for the purpose described.

8. In a cash register and indicator, the combination, with a series of operating-keys, of a movable bar extending across said keys, to which bar the keys become locked when displaced from their normal position, and an arrester applied to said bar to prevent it being reset, after being moved by the partial operation of a key, until it is given its full movement by the full operation of such key, substantially as and for the purpose described.

9. In a cash register and indicator, the combination, with a series of pivoted operating-keys, each provided with a hook, of a vibrating bar extending across said keys in front of said hooks and arranged to be engaged thereby when the keys are displaced from their normal position, a rack on said bar, a pawl arranged to engage the rack when the bar has been displaced from its normal position, a trip for disengaging the pawl from the rack when the bar has reached its limit of movement, and a latch for holding the pawl and rack out of engagement while the bar is being reset, substantially as and for the purpose described.

10. In a cash register and indicator, the combination of a series of operating-keys, a movable bar common to all of said keys and moved by the operation of any one of them, an arrester applied to said bar to prevent it being reset, after it is moved by the partial operation of a key, until given its full movement by the full operation of such key, and a locking-bar actuated by said movable bar

upon the operation of any key to lock all the unoperated keys from operation, substantially as and for the purpose described.

11. In a cash register and indicator, the combination of a series of operating-keys, a movable bar common to all of said keys and moved by the operation of any one of them, an arrester applied to said bar to prevent it being reset, after being moved by the partial operation of a key, until given its full movement by the full operation of such key, and a locking-bar actuated by said movable bar, upon the operation of a key, to move over the unoperated keys and hold them from operation until the operated key and movable bar have been actuated to their full extent and reset to normal position, substantially as and for the purpose described.

12. In a cash register and indicator, the combination of a series of operating-keys, a movable bar common to all of said keys and moved by the operation of any one of them, a rack on said bar, a pawl arranged to engage the rack when the bar is moved by the partial operation of a key to prevent the bar being reset until it has been given its full movement by the full operation of such key, and a locking-bar actuated by said movable bar upon the operation of a key to lock the unoperated keys from operation, substantially as and for the purpose described.

13. In a cash register and indicator, the combination of a series of operating-keys, a movable bar common to all of said keys and moved by the operation of any one of them, a rack on said bar, a pawl arranged to engage the rack when the bar has been displaced from normal position by the partial operation of a key, a trip for disengaging the pawl from the rack when the bar has been given its full movement, a latch for holding the pawl and rack out of engagement while the bar is being reset, and a locking-bar actuated by said movable bar upon the partial operation of a key to lock the unoperated keys from operation, substantially as and for the purpose described.

14. In a cash register and indicator, the combination of a series of operating-keys, a movable bar common to all of said keys and moved by the operation of any one of them and to which the keys become locked when displaced from their normal position, an arrester applied to said bar to prevent it being reset, after it is moved by the partial operation of a key, until given its full movement by the full operation of a key, and a locking-bar actuated by said movable bar upon the operation of any key to lock all the unoperated keys from operation, substantially as and for the purpose described.

15. In a cash register and indicator, the combination, with a series of operating-keys, each having a hook, of a vibrating bar extending across said keys and arranged to become hooked to the keys when the latter are displaced from their normal position, and a rack-and-pawl arrester applied to said bar

to prevent it being reset, after being moved by the partial operation of a key, until it is given its full movement by the full operation of such key, substantially as and for the purpose described.

16. In a cash register and indicator, the combination of a series of operating-keys, a movable bar common to all of said keys and moved by the operation of any one of them, and an oscillating locking-bar extending across the rear ends of the keys and actuated by said movable bar upon the operation of any key to move over and lock the unoperated keys, substantially as and for the purpose described.

17. In a cash register and indicator, the combination of a series of operating-keys, a movable bar common to all of said keys and moved by the operation of any one of them, an arrester applied to said bar to prevent it being reset, after it is displaced from its normal position by the partial operation of a key, until given its full movement by the full operation of said key, and an oscillating locking-bar extending across the rear ends of the keys and actuated by said bar upon the operation of any key to move over and lock the unoperated keys, substantially as and for the purpose described.

18. In a cash register and indicator having a series of operating-keys and a money-drawer or till, the combination of a movable bar common to all of said keys and moved by the operation of any one of them, a latch applied to said bar to support it in the position to which it is moved by an operated key, and a trip for said latch, actuated by the closing of the money-drawer to release the movable bar, substantially as and for the purpose described.

19. In a cash register and indicator having a series of operating-keys and a money-drawer or till, the combination of a movable bar common to all of said keys and moved by the operation of any one of them, a locking-bar actuated by said movable bar upon the operation of any key to lock the unoperated keys, a latch applied to said bar to support it in the position to which it is moved by the operation of a key, and a trip for said latch, actuated by the closing of the money-drawer, substantially as and for the purpose described.

20. In a cash register and indicator having a series of operating-keys and a money-drawer or till, the combination of a movable bar common to all of said keys and moved by the operation of any one of them, a locking-bar actuated by said movable bar upon the operation of any key to lock the unoperated keys, a latch applied to said bar to support it in the position to which it is moved by the operation of a key, a trip for said latch, actuated by the closing of the money-drawer, and means for holding said latch constantly out of operation when desired, substantially as and for the purpose described.

21. In a cash register and indicator, the combination of the operating-keys D, provided with the hooks m, and the bar K, extending across said keys immediately in front of the hooks m and movable with the keys D throughout their limit of play, substantially as and for the purpose described.
22. In a cash register and indicator, the combination of the keys D, bar K, provided with rack T and pin q, bell-crank U, provided with shoulder o, and latch V, substantially as and for the purpose described.
23. In a cash register and indicator, the combination of the keys D, provided with the hooks m, bar K, provided with rack T and pin q, bell-crank U, provided with shoulder o, and latch V, substantially as and for the purpose described.
24. In a cash register and indicator, the combination of the keys D, bar K, provided with rack T and pin q, bell-crank U, provided with shoulder o, latch V, and locking-bar W, actuated by the bar K, substantially as and for the purpose described.
25. In a cash register and indicator, the combination of the keys D, bar K, latch-arm Z, lug d', locking-bar W, actuated by the bar K, and a trip w for the latch-arm Z, actuated by the closing of the money-drawer C, substantially as and for the purpose described.

26. In a cash register and indicator, the combination of the keys D, bar K, latch-arm Z, lug d', locking-bar W, arm X, trip w, drawer C, and lever C', substantially as and for the purpose described.

27. In a cash register and indicator, the combination of the keys D, bar K, latch-arm Z, lug d', locking-bar W, arm X, bell-crank B', carrying screw b', and drawer C, substantially as and for the purpose described.

28. In a cash register and indicator, the combination of a series of operating-keys D, a vibrating bar K, extending across the same and moved by the operation of any one of them, the semi-cylindrical locking-bar W, and mechanism interposed between the bar K and the bar W for actuating the latter by the movement of the former upon the operation of any key, substantially as and for the purpose described.

29. In a cash register and indicator, the combination, with the wing G and means for actuating it, of the pendent link L, lever M, bolt N, and money-drawer C, substantially as and for the purpose described.
